UNITED STATES PATENT OFFICE.

ARTHUR W. BUTTERFIELD, OF ST. LOUIS, MISSOURI.

OIL-VAPORIZER.

1,129,845.

Specification of Letters Patent. Patented Mar. 2, 1915.

Application filed May 20, 1914. Serial No. 839,874.

To all whom it may concern:

Be it known that I, ARTHUR W. BUTTERFIELD, a citizen of the United States, and resident of St. Louis, Missouri, have invented certain new and useful Improvements in Oil-Vaporizers, of which the following is a specification containing a full, clear, and exact description, reference being had to the accompanying drawings, forming a part hereof.

My invention relates to improvements in oil vaporizers, in which a finely divided baffle is interposed between the source of oil supply and a steam line to atomize the oil in live steam before its entry into the steam line, and the object of my improvements is to inject into the steam line a stream of steam thoroughly impregnated with the minutest atoms of lubricant which will commingle with the steam in the steam line and be carried thereby to the remotest parts of the engine or other machinery subjected to said steam resulting in increased efficiency of the engine or other machinery and a saving in lubricant. I attain this object by an employment of the device hereinafter fully set forth in my specification, pointed out in my claims and illustrated by the accompanying drawings, in which—

Figure 1 shows my device as in use between a sight feed lubricator and a steam line; Fig. 2 is a vertical sectional elevation of the device of my invention detached from the sight feed lubricator and steam line; and Fig. 3 is a detail perspective of my preferred form of baffle.

In this application I have elected to show and describe my improved oil vaporizer in connection with a "sight, up-feed" lubricator, but do not wish to be understood as limiting myself to the use of my device in connection with this form of lubricator alone, as any other form of means for supplying lubricant to my improved atomizer in controlled quantities may be advantageously employed.

Referring by numerals to the accompanying drawings: 4 designates the oil reservoir of an ordinary "sight, up-feed" lubricator. To one side of the reservoir is located an indicator glass 5, and on the other side of the reservoir is a sight feed glass 6. At the lower end of the sight feed glass there is a valve 7 for regulating the flow of oil from the reservoir through the sight feed glass. Extending laterally from the upper end of

the reservoir and in communication with the upper end of the sight feed glass is a discharge valve 8.

9 designates a steam pipe, or a steam line 60 which is arranged for connection with a source of steam supply and with a steam engine or other machinery requiring lubricated steam for its operation.

10 designates a condenser pipe leading 65 from the steam line 9 to the discharge valve of the lubricator, and located in this condenser-pipe is a valve 11, whereby the steam may be cut off when it is desired to open the oil reservoir for purposes of filling or repair. 70

12 designates the body portion or casing of my atomizer, which is provided at its upper end with an internally threaded extension 13 arranged for connection with the discharge valve 8 of the lubricator. Within 75 the casing 12 below the point of connection with the discharge valve of the lubricator is a centrally perforated, horizontal wall 14 and in the upper end of the casing alining with the opening in the horizontal wall is 80 an internally threaded boss 15, which provides means for connecting the atomizer with a live steam pipe, such as 16, which is preferably tapped into the condenser pipe 10 and provided with a valve, such as 17, for 85 controlling the steam to the atomizer. Within the casing beneath the horizontal wall 14 is a shoulder 18, and resting against this shoulder is a baffle plate 19, whose uppermost face is convexed and which is provided 90 with a plurality of radially arranged slots at or near its periphery.

20 designates a second baffle plate, which is connected integrally with the plate 19 by a stem 21, whose uppermost face is convexed and through which plate there is formed a plurality of minute openings 95 22.

The lowermost end of the casing is internally threaded to receive a head 23 and projecting upwardly from this head is a 100 number of fingers 24 arranged for the support of the baffle plates 19 and 20. Formed on the bottom of the head 23 is a boss 25, having a threaded bore, and which is non-circular, externally, to provide for fully 105 seating the head by means of a wrench.

26 designates a pipe, including an elbow, which forms a communication between the atomizer and the steam line.

The practical operation of my improved 110 atomizer is as follows: Assuming the lubricator to be connected up as shown and pe-

riodically ejecting "drops" of oil in a common manner, it is to be understood that these "drops" will be carried by pressure from the condenser pipe, and be deposited 5 on the wall 14 of my atomizer, from which the "drops" will find the opening in said wall and be carried therethrough by live steam from the pipe 16 to the baffle plate 19. By reason of the high temperature of this 10 plate 19, due to its being located in the path of live steam, the oil will be "thinned" and be in better condition for comminution in passing through the slots in the plate 19 under the pressure of the steam. The 15 steam and comminuted lubricant after having passed through the baffle 19 are then forced through the minute openings in the second baffle which thoroughly impregnates all of the steam with the minutest atoms of 20 lubricant, and in this condition the lubricant is delivered to the steam line where it will be carried to the remotest parts of the engine or other machinery.

Having thus described my invention, what 25 I claim as new therein and desire to secure by Letters Patent of the United States therefor, is:

1. In a device of the class described, a 30 casing, separate and distinct means adjacent one end of the casing for connecting the casing with a source of oil supply and with a source of live steam supply, a fixed wall

within the casing having a perforation therein in the joint paths of oil and steam, a baffle, within the casing adjacent the perforated wall, having minute openings therethrough out of the direct path of steam and oil discharged through the opening in said wall, said casing having an outlet common to the steam and oil on the side of the baffle 40 opposite the perforated wall.

2. In a device of the class described, a casing having at or adjacent one end a steam inlet and an oil inlet, a fixed wall beneath said inlets and having a perforation therethrough, a baffle having a convexed surface imperforate in the direct path of steam and oil discharged through said perforation, but having minute perforations 45 out of said path of steam and oil, a second baffle spaced from the first mentioned baffle, means for detachably holding the baffles in place within the casing and said casing having an outlet common to the steam and oil, substantially as shown and for the purposes 50 stated.

In testimony whereof, I have signed my name to this specification, in presence of two subscribing witnesses.

ARTHUR W. BUTTERFIELD.

Witnesses:

E. L. WALLACE,
EDWARD E. LONGAN.
